CLAIM

The ornamental design for a space heater as shown and described.

DESCRIPTION

FIG. 1 is a front, right and top perspective view of a space heater, showing my new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is an enlarged view of detail 8 in FIG. 1.

The dashed broken lines depict portions of the Space Heater that form no part of the claimed design. The dot-dash broken lines in FIGS. 1 and 8 depict the boundaries of the enlarged views and form no part of the claimed design. The oblique shade lines in the drawings indicate a transparent surface.
